[57] CLAIM

The ornamental design for a case for an hand-held electronic calculator, substantially as shown and described.

DESCRIPTION

The ornamental design for a case for hand-held electronic calculator showing our new design;
 FIG. 2 is a front elevational view thereof;
 FIG. 3 is a rear elevational view thereof;
 FIG. 4 is a right-side elevational view thereof, the left-side elevational view thereof being essentially a mere image thereof;
 FIG. 5 is a bottom plan view thereof; and
 FIG. 6 is a rear elevation view of a case for a hand-held calculator showing a modified form of our new design; and
 FIG. 7 is a left side elevational view thereof, the right side being a mirror image and the front being the same as FIG. 2.
